(57) **CLAIM**

The ornamental design for an electric motorcycle, as shown and described.

DESCRIPTION

FIG. 1 is a top, rear, and left side perspective view of an electric motorcycle embodying our new design;

FIG. 2 is a bottom, front, and right side perspective view thereof;

FIG. 3 is a top, front, and right side perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof;

FIG. 9 is a bottom plan view thereof;

FIG. 10 is an enlarged and partial perspective view of portion 10 in FIG. 1;

FIG. 11 is an enlarged and partial perspective view of portion 11 in FIG. 1; and,

FIG. 12 is an enlarged and partial perspective view of portion 12 in FIG. 1.

The broken lines in the drawings illustrate portions of the electric motorcycle that form no part of the claimed design.

1 Claim, 12 Drawing Sheets
